UNITED STATES PATENT OFFICE

JOHN R. WALD, OF HUNTINGDON, PENNSYLVANIA

REFLECTOR BUTTON AND HOLDING MEANS THEREFOR

Application filed October 10, 1930. Serial No. 487,641.

This invention relates to reflecting signs, and more especially to a reflector button and a holding means therefor applied to a sign.

An object of the invention is to provide a reflector button of a specific shape adapting it to be readily held in position in a reflecting sign of the type used along roadways to be illuminated by the headlights of passing automobiles.

10 Another object is to provide a simple and effective means for holding such reflector buttons in position in the sign.

All these and other objects, as suggested herebelow, are attained by the method and 15 means now to be described, and illustrated in the accompanying drawings, in which—

Figure 1 is a side elevational view of a typical reflector button of this invention showing, in completely-assembled position, 20 the means for holding it in the sign.

Fig. 2 is a top plan view of the button of Fig. 1, in the sign.

Fig. 3 is a side elevational view of the button-holding means adapted for use with a 25 button of the contour now in general use.

Fig. 4 is a side elevational view of the sheet-metal holding means used in the device of Fig. 3.

Fig. 5 is a cross sectional view through a 30 vertical diametral plane of applicant's improved reflector button.

Like numerals refer to like parts throughout the several views.

The invention consists essentially of a reflector button cast or otherwise formed to 35 the shape substantially as shown in Figs. 1 and 5, and made of some light-reflecting material such as glass, either colored or plain. A cross section of the button through a plane at right angles to its longitudinal axis at any point, is circular.

The button 10, Fig. 1, has a convex lens-like reflecting surface 10A, projecting outwardly from the sign surface or plate 11. 45 Plate 11 is perforated with a series of holes so arranged as to form the particular letters or words of the sign. A concave mirror-like reflector 12 is positioned across the lower or inner end of button 10, in the manner as shown in Fig. 1, and held in place by a

pressed-metal cap 13, shaped somewhat as shown. Cap 13 rests against a disc-like felt pad 14, the resiliency of which when pressed in place holds the cap on the button and the reflector tightly in proper position between them, as well as aiding in preventing breakage due to strain or jars, as when erecting the sign or replacing the buttons.

Surrounding each button 10 is a cylindrical-like pressed-metal container 15, tapered toward one end, as shown, to accommodate a corresponding taper of the button 10 and adapted to surround the cap 13 and having extending lugs 16 which may be flanged over as shown, after the parts are in assembled relation, to press a disc-like cover 17 against the felt pad 14 to hold the parts in properly assembled position.

The sign-engaging end of container 15 abuts against the edges of plate 11 immediately surrounding the hole in which the container is positioned, and a plurality of lugs 18 are adapted to pass through the hole and be clinched over on the outer surface of plate 11, as shown in Figs. 1 and 2, to prevent the assembled reflector unit from being pushed into the sign.

It will thus be seen by this construction that button 10 may be readily and permanently fastened within its container 15 by engaging in the taper of the container in one portion and being held from dropping out, by the assemblage above disclosed, at the other end; and the completely assembled unit containing the button 10 is then positioned through its hole in sign plate 11 until the rim around the top end of container 15 abuts against the inner edge of plate 11, when lugs 18 are clinched over on the outside of the plate to hold it firmly in position.

In the event of breakage or other failure of the button 10, the entire unit may be readily removed from the sign and replaced with a fresh one, and afterwards the old container assemblage used again with a new button.

A modification utilizing the standard form of reflector button 19 is shown in Figs. 3 and 4. Here the container is cylinder shaped, as shown at 20, and sign plate 11 has the sur-

face of each letter raised up as shown in Fig. 3, which raised surface is pierced by the holes for the various reflector buttons. The lens-like upper surface of button 19 abuts 5 against the edge of the hole and prevents the buttons coming out through the front. The upper edge of container 20 abuts against the inner surface of plate 11 and there are two flanges 21-22 adapted to extend through the 10 opening of the plate and be flanged over to hold the container in position thereon in the same manner as in the construction above described.

It should be noted that the holes cut in the 15 sign plates 11 in both instances have recesses cut in their peripheries to accommodate the flanges 18 and 21-22 respectively. Also the holding discs 17 may have similar recesses cut for flanges 16.

20 It is to be understood that the present disclosure is for the purpose of illustration only, and that the invention is not limited thereto. To those skilled in the art, many modifications of the invention will be readily 25 apparent, and it will also be obvious to such skilled persons that part of the method and means may be used without other parts thereof, many such combinations of the parts readily suggesting themselves. Therefore, 30 it should be, and is to be distinctly understood that for a definition of the limitations of the invention, reference must be had to the appended claims.

Having now described the invention, what 35 is claimed as new and for which Letters Patent of the United States is desired, is:

1. A sign comprising a flat holder and a plurality of reflecting units therein, each including a lens formed of a cylindrical body 40 of glass having the outer end convex and the side walls immediately adjacent thereto tapered inwardly toward such end, and a container for said reflecting unit adapted to hold it through engagement of the tapered 45 portion thereof with a similar tapered portion of the container, one end of the container abutting the under surface of the holder and having lugs extending therethrough and flanged over on the outer surface of said 50 holder to retain the unit in position therein.

2. The combination in a sign of an apertured plate, light reflecting buttons in said apertures, a container around each of said buttons and held in position in its aperture, 55 a second container within the first and surrounding the inner end portion of said button, a concave reflector positioned between the inner end of the button and the inner container, and a resilient member engaging the 60 end of the inner container and held in position within the outer container.

3. In combination, a cylinder-like container having open ends and flangable lugs, an apertured plate, a light reflecting member 65 extending through said aperture and encased

in said container, one end of the container with its flanges being adapted to removably position the container around the aperture in said plate, and the flanges at the other end of the container being adapted to hold the 70 light reflecting unit therein.

4. In combination, a tapered container, a second container positioned therein and pointing in the opposite direction and having an opposite taper, and a light-reflecting 75 member adapted to be held within both said containers and being similarly tapered.

Signed at Huntingdon, in the county of Huntingdon and State of Pennsylvania, this 6th day of October, A. D. 1930.

JOHN R. WALD.
